UNITED STATES PATENT OFFICE.

MORIS GERINGER, OF YONKERS, NEW YORK, ASSIGNOR TO GERINGER BROS., OF NEW YORK, N. Y., A PARTNERSHIP CONSISTING OF MORIS GERINGER AND ISIDORE GERINGER, OF YONKERS, NEW YORK.

DESIGN FOR A DROP LAMP FIXTURE.

Application filed September 17, 1926, Serial No. 19,099. Term of patent 3½ years.

To all whom it may concern:

Be it known that I, MORIS GERINGER, a citizen of the United States, and a resident of Yonkers, county of Westchester, and State of New York, have invented a new, original, and ornamental Design for a Drop Lamp Fixture, of which the following is a specification, reference being had to the accompanying drawing, forming a part thereof.

The figure in the drawing shows a perspective view of the drop lamp fixture.

I claim:

The ornamental design for a drop lamp fixture substantially as shown.

MORIS GERINGER.
